LIQUID LEVEL GAUGE OR SIMILAR ARTICLE

Donald G. Gruett, Manitowoc, Wis., assignor to Oil-Rite
Corporation, Manitowoc, Wis.

Filed Feb. 8, 1971, Ser. No. 113,780

Term of patent 14 years

Int. Cl. D10—04

U.S. Cl. D52—6

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a front perspective view of a liquid level gauge or similar article showing my new design.

FIG. 2 is a front elevational view thereof;

FIG. 3 is a right side elevational view thereof, the left side being a mirror image thereof;

FIG. 4 is a rear elevational view thereof;

FIG. 5 is a top plan view thereof;

FIG. 6 is a sectional plan view as taken from lines 6—6 of FIG. 2;

FIG. 7 is a front perspective view of another form of my new design wherein the upper and lower fittings have hexagonal heads on the front faces thereof;

FIG. 8 is a front elevational view thereof;

FIG. 9 is a right side elevational view thereof, the left side being a mirror image thereof;

FIG. 10 is a rear elevational view thereof;

FIG. 11 is a top plan view thereof;

FIG. 12 is a sectional plan view as taken from lines 12—12 of FIG. 8.

I claim:

The ornamental design for a liquid level gauge or similar article, as shown.
